UNITED STATES PATENT OFFICE.

GEORGE F. BRINKERHOFF, OF BUCYRUS, OHIO.

IMPROVEMENT IN STOVE-PIPE COLLARS AND THIMBLES.

Specification forming part of Letters Patent No. 159,150, dated January 26, 1875; application filed July 18, 1874.

To all whom it may concern:

Be it known that I, GEORGE F. BRINKERHOFF, of Bucyrus, in the county of Crawford and State of Ohio, have invented a new and valuable Improvement in Collar and Thimble for Stove-Pipes; and I do hereby declare that the following is a full, clear, and exact description of the construction and operation of the same, reference being had to the annexed drawings making a part of this specification, and to the letters and figures of reference marked thereon.

Figure 1 of the drawing is a representation of a sectional view of my collar and thimble. Fig. 2 is a front view of the same. Fig. 3 is a perspective view of my improved thimble, showing the manner of turning in the strips or branches; and Fig. 4 is an end view of the said thimble with alternate strips turned back against the inner wall of a flue.

This invention has relation to means for rigidly securing into the pipe-hole in the inner wall of a flue a thimble; and the novelty consists in a flange upon the inner end of the said thimble, preventing it from being pushed through the pipe-hole, and in branches cut from the other end, which are bent alternately inward around the outer end of a stove-pipe inserted into the said thimble, and outwardly against the wall of the flue, whereby the said thimble is prevented from being withdrawn from the said pipe-hole, and the pipe is prevented from penetrating through the pipe-hole farther than is necessary. It also consists in a collar applied around the pipe-hole of a flue upon the inside of an apartment, having a flange to receive the flange upon the thimble, which collar is embedded into the plastering in new houses, or is secured thereon in old houses, causing a neat and appropriate appearance to be given to the joint.

In the annexed drawings, A designates a chimney, into which a pipe is passed through the wall of a room bounding the said flue, in the usual well-known manner. B designates a collar of wood, metal, or any other suitable material, having a flange, b', and a circular bead, b, raised around its central perforation, the diameter of which is somewhat greater than the diameter of the pipe to be used. This collar is applied, when used with houses in pro-

cess of building, upon the bare wall around the stove-pipe hole, and it is in this case embedded in the plastering; but it may be put upon the plastering either in new or old houses, if desired. C designates a thimble of sheet metal, preferably of cylindrical form, upon the front end of which a flange, c, is made, its rear end being cut into a suitable number of strips or branches, c' d, in the length of the thimble. If, now, the thimble C be inserted into the pipe-hole, its branched end foremost, the flange c will shoulder against the inner flange, b', of the collar B, and will prevent it from being pushed into the flue and falling to its bottom—an event which is not of unfrequent occurrence with other thimbles. The hand is now inserted through the thimble into the flue, and every alternate strip c' is bent radially down against the wall of the flue, as shown in Figs. 3 and 4, causing the thimble to be rigidly held against falling inward into the room and covering and soiling everything with which it comes in contact. D indicates a section of a stove-pipe of the usual construction, which is inserted into the thimble until its inner edge is flush with the inner wall of the flue. The remaining strips d are then bent over and inward upon the inner surface of the pipe-section D, and are forcibly flattened thereon, thus providing hooks, which prevent it from penetrating too far into the flue and choking or impeding the draft. E designates a hook, which is secured at one of its ends to the collar B, or to the wall of the apartment, and by the other to the pipe-section, and which prevents it from falling inward into the room.

It will be seen from the above description that neither the thimble nor the pipe-section can be thrust into the body of the flue or caused to fall into the room, and that, in consequence, I not only have avoided choking up the flue, but also the disagreeable consequences entailed by the falling of soot-covered thimbles and sections of pipe into the room; also, that, by using a collar which may be of any desired degree of ornamentation, I have converted a usually unsightly part of a wall into one which will please the eye and add greatly to the appearance of the room.

The circular bead b of the collar B being of somewhat greater diameter than the pipe sec.

tion E, a space is left between it and the pipe, which I preferably fill with cement, plaster-of-paris, or other suitable compound, and thus prevent any escape whatever of gas or smoke into the room, thereby effectually preventing the deposit of soot upon the collar or upon the walls of the room.

I am aware that a collar, a thimble, and a pipe-section are not new, and therefore I do not claim such inventions, broadly.

What I claim as new, and desire to secure by Letters Patent, is—

1. The combination of the collar B, having

a flange, b', and a bead, b, the thimble C, having a flange, c, and fastening-strips c' d, and the pipe-section D, substantially as specified.

2. The thimble C, having upon one end a flange, c, and upon its other end fastening-strips c' d, substantially as specified.

In testimony that I claim the above, I have hereunto subscribed my name in the presence of two witnesses.

GEORGE F. BRINKERHOFF.
